UNITED STATES PATENT OFFICE.

CHARLES B. ULRICH, OF JAMESTOWN, NEW YORK.

HUNTING BOAT.

Application filed December 24, 1926. Serial No. 156,796.

My invention relates to an improved form of hunting boat of the kind generally known as duck boats and is characterized by several improved features as follows: first, the 5 hull of the boat is so shaped that it lies low in the water, that the draft is a minimum, that the occupant may be in a comfortable sitting or reclining position and yet have his head substantially even with the upper 10 edge of the coaming of the boat, and that the hull as a whole shall have ample buoyancy in connection with the proportions required to accomplish the results referred to; second, the provision of doors for closing the 15 major part of the cock pit when the boat is approaching its quarry, which doors are spring actuated so that they will move to vertical position when released to afford free action of the hunter at the instant he desires 20 to fire; third, the provision of propelling mechanism by which the hunter may propel the boat by operating devices contained in the boat, for example a screw propeller connected by suitable devices in the boat with a 25 driving wheel which may be turned by a suitable handle, and steering mechanism actuated from within the boat by the feet of the hunter.

The advantages of my improved construction are that the boat may be propelled slowly without disturbance of any kind and without there being any motion visible from the outside of the boat, of the person doing the propelling; also that the hunter is entirely concealed with the exception of the 30 upper part of his head during motion of the boat to a point where the quarry is expected to be found, or while waiting for the game to collect at a selected location and yet at the same time affording the hunter practically as great freedom during firing as he would have in an open boat; in addition to these advantages the hunter is in a comfortable position at all times instead of being 35 in a cramped position as has commonly been the case heretofore with duck boat constructions, and further, this position is adapted to permit instant action of the hunter at the time of firing without changing his position, at which time the open doors afford him a wide range of vision and permit him to fire in any desired direction.

My invention will best be understood by reference to the accompanying drawings 55 showing a preferred embodiment thereof in which

Fig. 1 shows my improved boat in side elevation,

Figs. 1^a, 1^b and 1^c are transverse sectional views of the hull of the boat shown in Fig. 1 taken respectively along the lines a—a, b—b and c—c,

Fig. 2 is a plan view of the boat shown in Fig. 1,

Fig. 3 is a detail view of propelling mechanism adapted for use with the boat shown in Figs. 1 and 2, taken along the line 3—3 in Fig. 2,

Fig. 4 is a sectional view of the parts shown in Fig. 3, taken along the line 4—4,

Fig. 5 is a detail view of a part of the steering mechanism employed in the boat shown in Figs. 1 and 2,

Fig. 6 is a sectional view of the devices shown in Fig. 5 taken along the line 6—6,

Fig. 7 is a detail view of the door locking mechanism used in connection with the boat shown in Figs. 1 and 2, this view being taken along the line 3—3 in Fig. 2, and

Fig. 8 is a detail rear end view to an enlarged scale of the doors, showing their relation to each other, this view being taken along the line 8—8 in Fig. 2.

Similar numerals refer to similar parts throughout the several views.

As shown in Fig. 1 the boat consists of a hull 10 having a water line 11 which is but slightly below the deck of the boat. Below the water line the hull of the boat indicated at 12 is of gradually increasing depth, as indicated by the lines of the hull in Fig. 1 and the cross sections thereof shown in Figs. 1^a, 1^b and 1^c, until a position aft of mid ships is reached where the maximum depth or draft is found. A cock pit is formed in the boat by a coaming 13 extending for nearly half the length of the boat, of a width sufficient to give the occupant opportunity for free movement. The coaming is taken of a height to protect the cock pit from the wash that may flow over the deck and the total depth of the hull at the cross section indicated in Fig. 1^c, is preferably such that the occupant of the boat sitting at this point in a somewhat reclining position will have his head but partly above the top edge of the coaming. Aft of the section indicated in Fig. 1^c the cross section of the hull rapidly tapers to substantially that indicated in Fig. 1^a to afford a suitable clearance for a propeller 14 and rudder 15, the lower end of the rudder post 15^a being pivoted in a

snag bar 16 extending under the propeller to constitute a guard protecting the propeller and rudder from weeds and snags.

The forward part of the cock pit is provided with doors 17^a and 17^b extending from the front end of the cock pit nearly to its after end and of a width to completely close the cock pit laterally. The open space at the after end of the doors 17^a and 17^b is to afford the occupant of the boat opportunity to see about him sufficiently to navigate the boat. The doors 17^a and 17^b are connected at their outer longitudinal edges by spring hinges 18 with the adjacent coaming, the springs in the hinges tending to move the doors from horizontal position to substantially vertical position as indicated in dotted lines at 17^c in Fig. 1, for which position the entire cock pit is open and affords free movement to the occupant of the boat. As shown in Figs. 7 and 8, one of the doors, for example the door 17^a, is provided with a locking bolt 19 mounted in a guide 20 so that its forward end may project into engagement with a suitable aperture or recess formed therefor in the forward coaming 13. The other end of the bolt 19 is connected with an operating rod 21 having a suitable guiding support 22 at the after end of the door 17^a, beyond which the rod 21 is extended slightly and has secured to it a knob 23, by which the bolt 19 may be moved from engagement with the coaming or into engagement therewith as desired. With this construction, the door 17^b preferably is provided on its inner edge with a projecting ledge 17^d below the adjacent edge of the door 17^a, so that the bolt 19 will hold both of the doors in their horizontal position against the action of the springs in the hinges 18.

In using the boat, the doors 17^a and 17^b are held in their closed or horizontal position by the bolt 19, at all times that it is desired to have the boat and hunter as inconspicuous as possible, and at the instant it is desired to fire at the game, the hunter, first having his gun in readiness below the doors, pulls the knob 23, the spring hinges 18 at once move the doors 17^a and 17^b to their open position and at the same time the hunter raises his gun and fires in the desired direction.

As indicated in Fig. 2, and more clearly shown in Figs. 3 and 4, the propeller 14 is mounted on a shaft 24, the inner end of which has rigidly secured thereto a grooved wheel 25 engaged by a belt 26, which belt passes around idler sheaves 27 and a driving wheel 39. The sheaves 27 are preferably supported by ball bearings 40 on studs 41 supported in turn by a bracket 42 secured to the hull 10 of the boat, said bracket being preferably extended to also support a ball bearing 43 supporting the forward end of the shaft 24. A tightener sheave 44 is

shown engaging the belt 26, carried by a stud 45 mounted on an arm 46 pivotally connected to the hull at 47, so that the belt 26 may be kept taut. The wheel 39 is mounted for rotary movement on a stud 48 supported from the hull 10 and said wheel is provided with a handle 49 by which the wheel 39 may be conveniently turned in either direction, as desired, by the occupant of the boat, thus through the devices just described, moving the boat ahead or astern as desired. If desired, the wheel 39 and the tightener sheave 44 may be mounted on their respective studs 48 and 45 by means of ball bearings as indicated to reduce friction of the driving mechanism to a minimum. It will be understood that the belt described may be of any convenient kind, round or flat, and either frictionally engage the wheels or that it may comprise a chain, and that the wheels and sheaves are conformed in any case to suit the particular type of belt employed.

The rudder post 15^a of the rudder 15, extends into the hull of the boat where it is secured at its upper end to a tiller bar 28, the ends of which are connected in turn by flexible links 29, 29 with the rear ends of operating bars 30, 30. The bars 30 as indicated in Fig. 6 are preferably rectangular in cross section and supported in suitable guideways 31 on edge, said guideways being in turn secured to the frame work of the boat. The shape of the bars 30 and their co-operating guideways 31 prevents rotary movement of the bars and serves to hold foot lugs 32 carried by the bars in a position extending horizontally towards each other, for convenient engagement by the feet of the occupant of the boat. The forward ends of the bars 30 are connected by flexible links 33 with the ends of a cross bar 34 pivotally supported at its mid portion under the deck of the boat as indicated at 35 so that the rudder 15 may be operated entirely by one of the bars 30 if desired, since the several links referred to will positively move either bar 30 in an opposite direction to the direction of movement imparted to the other one of the bars 30. I find it convenient to support the link connections 29 by additional links 36 supported at their upper ends by suitable devices, for example screw eyes 37 from the underside of the deck of the boat. In this way the links 29 may be held in proper position and prevented from rubbing on the hull of the boat.

To make the boat as inconspicuous as possible, I find it advisable to cover the deck and doors with grass, rushes, or grass matting as indicated at 38 which causes the boat to blend in considerable measure with its surroundings, particularly when using the boat where there is sea grass or reeds.

From the above description it will appear that I have provided a construction of boat affording the occupant a convenient and comfortable position and at the same time insuring that the boat need project but a few inches above the surface of the water, and permitting the occupant at the same time to propel the boat and steer it as desired, all of which may be accomplished with the doors in their closed position, and at the same time the boat construction results in the center of gravity of the load being aft of midships which is a condition to be desired to afford control of the navigating of the boat, and the proportions of the boat further provide ample buoyancy to meet all requirements; in addition to the advantages pointed out my improved construction, affords the occupant of the boat practically unrestricted freedom in firing when the instant arises for shooting the game.

The hull of the boat may be made in any manner known to the art, for example of wood or fabric on a suitable framework, or of sheet metal, and since the kind of construction is not a part of the present invention, it is not particularly shown or described. While I refer to the hinges as spring hinges for the purpose described, it will be understood that I may employ any desired arrangement of hinges and springs for supporting and opening the doors as described.

While I have shown my invention in the particular embodiment above described, it will be understood that I do not limit myself to this exact construction as I may employ equivalents known to the art at the time of the filing of this application without departing from the scope of the appended claims.

What I claim is:

1. A hunting boat consisting of the combination of a hull having cross-sections from bow to aft of mid-ships of gradually increasing displacements and graded from a slightly curved line adjacent the bow to a double reversed curve of maximum draft aft of mid-ships conformed substantially to the contour of the human body in reclining position, a deck partly covering the hull, and having an elongated opening therein forming a cock-pit, doors hinged at their longitudinal outer edges to the deck to close the major portion of the forward end of said cock-pit, springs tending to move said doors to open the cock-pit, and a latch for holding said doors in closed position against the action of said springs.

2. A hunting boat consisting of the combination of a hull having its displacement lines conformed substantially to the contour of the human body in reclining position, a deck partly covering the hull, a propeller under the after portion of the hull, a driv-

ing wheel in the boat, a propeller shaft extending into the boat, a belt wheel on the inner end of said shaft, a belt connecting said wheels, sheaves for changing the direction of said belt, and a handle on said driving wheel for operating the same.

3. A hunting boat consisting of the combination of a hull having its displacement lines conformed substantially to the contour of the human body in reclining position, a deck partly covering the hull, a propeller under the after portion of the hull, a propeller shaft extending into the boat, a belt wheel carried by said shaft, a wheel for driving said belt, a tightener for said belt, an operating handle connected with said driving wheel for driving the same, a rudder, bars inside of said boat and below said deck and connected with said rudder to operate it, and foot lugs extending from said bars for engagement by the feet of the occupant of the boat.

4. A hunting boat comprising the combination of a decked hull having a cock pit, doors hinged to the longitudinal edges of said cock pit to form a cover for the same, springs tending to open said doors, and a catch for holding said doors in closed position against the action of said springs.

5. A hunting boat comprising the combination of a decked hull having a cock pit, doors hinged to the longitudinal edges of said cock pit to form a cover for the same, springs tending to open said doors, a catch for holding said doors in closed position against the action of said springs, said catch being at the forward end of said doors, a rod extending from said catch to the after end of said doors, and a handle on the after end of said rod for operating it to in turn operate said catch.

6. A hunting boat comprising the combination of a decked boat having a cock-pit, a hinged door having a closed position across the opening of said cock pit and an open position clear of said opening, spring mechanism tending to open said door, and a catch for holding said door closed.

7. A hunting boat comprising the combination of a decked boat having a cock-pit, a door having a closed position across the opening of said cock pit and an open position clear of said opening, spring hinges supporting said door and tending to move it to its open position, and a catch for holding said door closed.

8. A hunting boat comprising the combination of a hull, a deck partly covering said hull and having an opening forming a cock pit, a door hinged to the edge of said cock pit for closing the same, and a grass covering on said deck and door.

In witness whereof, I hereunto subscribe my name this 21st day of December, A. D. 1926.

CHARLES B. ULRICH.
